ATTORNEY.

Patented Oct. 12, 1926.

UNITED STATES PATENT OFFICE.

GEORGE C. BATZ, OF TOPEKA, KANSAS.

SPRING.

Application filed July 10, 1925. Serial No. 42,765.

My invention relates to elliptic springs, such as commonly used in the construction of railway cars, but do not confine my invention to such application alone.

5 The object of my invention is to provide an elliptic spring, the leaves of which are uninterrupted by perforations or other connecting means severing any portion from the leaf of the spring.

10 A further object of my invention is to provide an elliptic spring with the adjacent ends engaging in the seat block, and having means to retain the blocks in alignment therewith.

15 A still further object of my invention is to provide a block functioning as a seat for the adjacent ends of the springs and adapted to remain in proper working relation having guiding means and engaging the leaves 20 reducing the maximum span automatically.

These and other objects will be herein-after more fully explained.

Referring to the drawings.

Fig. 1 is a top view of a pair of springs 25 functioning as a unit.

Fig. 2 is a side view of the spring.

Fig. 3 is an enlarged detailed view of one end of the springs the seat block being in section.

20 Fig. 4 is a cross section of the block taken on line 4-4 as shown in Fig. 5 looking in the direction of the arrows.

Fig. 5 is a plan view of the block.

Fig. 6 is an edge view partly in section 35 being taken on line 6-6, looking in the direction of the arrows in Fig. 5.

Fig. 7 is a detailed view of one end of one of the inside leaves of the spring, part in section.

40 In Figure 1 is shown two springs centrally connected by clips 1 and the ends thereof engaging in blocks 2, the said blocks having side and end walls 3, functioning as guides for the ends of the springs. 5 is the body of the block, having a plurality of perforations 6 positioned therein, 7 is a web functioning as a separator for the springs, said separator being integral with the body and walls of the blocks, 8 is a 45 laterally extending portion of the body functioning as a bearing on which the springs will rest when compressed to their maximum, and along the angle from the ridge 9 to the depth of the depressions as at 10 55 will be the engaging points for the minimum load.

The ends of the inside spring leaves 11 have a plurality of bosses 12 and 12', said bosses adapted to seat in apertures 6 functioning as guiding means for blocks 2 holding 60 said blocks in alignment with the ends of the spring leaves for proper engagement during the reciprocations of said springs.

It will be understood that when bosses 12' enter their respective apertures the leaf 65 springs 11 will engage on the bearing 8 functioning as a fulcrum point for the outer ends of the spring leaves. It is then possible that bosses 12 will disengage from their respective apertures and in such case 70 the bosses 12' are relied upon to retain the block in its proper position relative to the ends of the spring leaves.

The said bosses are made by compressing the spring member as shown in Figure 7, 75 by this process the leaf of the spring is not weakened and it is also means for eliminating the use of shackles, bolts, and eyes formed by the leaf all of which tends to shorten the duration of the springs. The 80 leaves of the spring are held in alignment by means of the clips 1 and at the ends by means of the blocks 2, and by detaching clips 1 any one of the leaves of the spring 85 can be removed, repaired and replaced without disturbing other parts of the spring unit.

When the spring is normally engaged, the ends of the second leaves of each half as at B engage on the adjacent inside springs over the ridges 9 and the third leaves of each 90 half as at C engage over the laterally extending portions 8, the latter being a protection for the two plies of the springs under maximum load engagement, therefore it is easily discerned how the span of my elliptic spring is diminished in its bearing points 95 automatically increasing the resilient strength as the load is imposed thereon.

Such modifications may be employed varying the shape and the position of the apertures and likewise the bosses engaging therein, and also variation of the width of the block for varying the distance of the bearing points relative to the span of the springs or other modifications that lie within the 100 scope of the appended claim and having thus described my invention what I claim as new and desire to secure by Letters Patent is:—

110 In a spring, springs comprising two halves the said halves comprising a plurality of leaves, two bosses on each end of

the inside leaves of said springs, said bosses being separated and in longitudinal alignment with their respective leaves, blocks engaging between the ends of the halves of said springs, the said blocks having ridges near the outside thereof, apertures passing through the apex of said ridges, said apertures adapted to receive the inside bosses on the ends of said spring leaves as securing means for pivotal engagement of said leaves

on the apex of said ridges, laterally extending members on the inside edges of said blocks, apertures cutting into the sides of said members, said apertures adapted to receive the inside bosses on the ends of said spring leaves as securing means for pivotal engagement of said springs on said laterally extending members, for the purpose set forth and described. ¹⁵

GEORGE C. BATZ.
